Suspension Dock.

Patented May 13, 1831.

Thomas Evans and John Parsons, of New York City,
Solex Patent

The Schedule referred to in the Solex Patent and making part
of the same containing a description in the words of the said Thomas
Evans and John Parsons, themselves, of their improvement in the
apparatus for lifting Ships and other vessels called the "Hydrostatic suspen-
sion Dock."

To all whom these presents shall come. We do know
that we Thomas Evans (machinist) and John Parsons (shipcarpenter)
of the City and State of New York, have invented, made and applied
to use a new and useful improvement in the art of lifting ships and
other vessels, for inspection and repair, called Evans and Parsons
Hydrostatic suspension Dock, and that the following is a full
and exact description thereof, to wit, Two piers, wharfs, or
other suitable structures are formed at right angles to the shore or
current of the River, by driving piles in the bed thereof, in precisely the
same manner as such piles have been constructed before, for screw docks
and other contrivances when the ships are lifted vertically out of the
water. If we suppose this dock to be capable of raising a ship
of one hundred tons, it should be one hundred and twenty feet in
length and thirty six in width between the piers, having a clear lift
of fourteen feet, this being a convenient size for vessels of that class,
but it is evident that the dimensions of the docks must vary to suit
the craft required. The piles forming the wharfs or each side
of the piers or dock being driven with great care and at as equal distances
asunder as possible, are secured together at the level of the piers by two
large and solid pieces of oak timber called plates, running the whole
length of the dock including the head thereof at the land end. The
use of this extension will be shown hereafter. As the dock we have as yet
found that numerous of piles would be eight feet apart in the shore
banking of the dock into the forward plates which rest on and are firmly
secured to the piles last mentioned. - Spurting are made to receive
large and even dock wheels, if possible having ample pedestals to

© 1851

May 13, 1831

support them (the wheels) that they may be freely on their bearings. These wheels may be about two feet in diameter, and are to be arranged that the propelling shall be easily on the car to be drawn each

pair of piles the rotation being longitudinal of the dock. The edge (rim) of the roach wheels may now (one can be simply a shallow groove) take a sheave of a block (a pulley) & is made to receive a tngle chain instead of a rope. In case the wheels are made in this manner, the falls that are intended to prevent accidents would be made to fall into the chain, when the ship is in the act of raising out of the water.

On the other hand if it should be deemed advisable to fall the wheels instead of the chains, then the wheels should be made with teeth of such a form as will insure their passing in and out freely from the openings of the tngle chains, without catching. A portion of the edge of the wheels being notched to receive two falls on each side, the teeth of the wheels prevent the chains from slipping when the machine is at rest.

Cradle beams are provided similar to those used for lifting ships in a variety of ways. The construction of which are so well understood that they need not be described. The length of these beams are governed by the size of the dock. Two of these beams form a section, they are kept about two feet apart and are planked from one to the other on the inner side. This space being filled with ballast to make the cradle stiff. Strong chains pass down over the aforesaid roach wheel, and are strongly fastened to the beams forming the cradle, one chain on each side sustaining a section. The other ends of the chains are fastened to two pieces of timber placed directly over the plates and parallel therewith stretching from the River end of the dock to the wharf. These pieces are called the drawing frame. There are two drawing frames, one on each piece over their respective plates. These pieces are firmly held at a sufficient distance apart to allow the roach wheels and chains over them to come together without touching. These frames have a horizontal motion of what ever vertical lift is required to raise the ship. The drawing frames are guided in their passage backwards & forwards by friction blocks having flanges to them, on which they litterally

May 13, 1831

The chains appearing coming up from the beams through the plates, and passing over the rock wheels, as far as their centre, are fastened to the drawing frames in a particular manner, of which more hereafter. At the land end of the dock and directly ^{in a line} with the drawing frames are placed two cylinders one over each plate on either side of the dock. The extremities of which extend in the beginning before the piston of below receiving the cylinders in their places, which is accomplished by bolting pieces of timber called fusing timber to the plates. The thickness of these pieces being such that the tops of ^{them} are in a line with the centre of the cylinders, which having projections cast on each side called fins of sufficient breadth and thickness, likewise having other fins, running at right angles to the body of the cylinders on the underside of the first mentioned fins, these last are let into the fusing timber their whole length, say three inches. Bolts being now passed through the longitudinal ^{fins} of fusing timber, and plates are firmly thereby secured to the dock. Those cylinders are intended to act as hydrostatic pumps, the piston being drawn inwardly in the operation of lifting. They consequently must have a piston similar to a steam engine with a rod passing through a stuffing box. This rod must be of sufficient size to haul up one half the united weight of the ship and cradle. The space between the heads of the cylinders and the ends of the drawing frames when the cradle is run to its greatest depth must always be somewhat greater than the distance the ship is to be elevated. A steam engine is to be placed in a convenient situation as possible to which will be attached two pumps, for forcing water into the cylinders. There must always be two pumps, one to each cylinder, and there must never be any communication between those pumps or the pipes leading from them to the cylinders, for reasons given hereafter. We will now suppose a ship to be floated in between the plates and raised in a proper position to be raised. The piston being run out their whole length, they are each strongly attached to the aforesaid drawing frames. The pumps being put in operation the piston of the hydrostatics are drawn into their respective cylinders the chains to which the latter as before mentioned fastened to the drawing frames, the vertical motion of the ship and cradle is converted into a horizontal one by the chains passing over the aforesaid rock wheels, it is evident of the piston continuing to

May 13, 1831

soever the ship will be drawn up as long as that vertical controversy. The weight being now completely lifted out of the water. The pumps being stopped the weight of the ship is sustained by the aforesaid falls. on the coach wheels they likewise form a perfect security against accidents while the ship is lifting the hydrostatics with their respective pumps must bear more equal as possible or the ship will be farther advanced on one side than the other there being no communication between the cylinders. If the pumps are equal in their boxes and length of stroke both sides of the cradle must come up level no matter how unequal the load may be.

The operation of drawing the ship is quite a different work. The friction of the machinery and weight of the cradle being so unequal. That in attempting to let down a ship by opening two orifices of equal diameter in each Hydrostatic the side which moved easiest kept gaining rapidly on the other by the weight of the ship being thrown on that side until utter destruction ensues. To correct this evil and which the Patentees consider a most important feature in their invention. is what we term a self-regulating apparatus. This consists in the insertion of a pipe into the head of each cylinder. each of these pipes passing in a diagonal manner to the back end of the other cylinder. each of these pipes have a stop cock in them for shutting off the communication when the ship is lifting there are likewise two discharging cocks, the use of which is to let the water out of the cylinder when necessary. Now let us suppose a ship ready to be let down. The piston are forced back sufficient to release the falls on the coach wheels, the stop cocks first mentioned in the diagonal pipes are opened, the water in either cylinder being all forced by the piston is acted on by the weight of the ship cause it to escape with great force. but it is shown that the water does not escape into the atmosphere but is compelled from before one piston to the rear of the other this produces a most perfect equilibrium in the center of the ship, for if one piston be drawn by fifty tons more than the other, it cannot move an inch, till the other moves also, because if the second piston remains at rest the first has no place to discharge its water. therefore whatever power the first piston has over the second it imparts just so much to it. They therefore move together. This was confirmed by a trial

May 13, 1831

apparatus, when the ship is afloat. the cylinders are as full of water as ever it being merely conveyed from one cylinder to the other, when the next operation takes place, the discharging cock, ^{is open} affords, to let the water escape. In repairing a ship's bottom it is often necessary to lower a section without disturbing the rest. one method to do this is to attach screws to the end of each chain, the female being made to stand in such a position between the drawing frames as to be nearly horizontal. the female screw would have a sufficient support to revolve against, having spiral teeth on their peripheries. an endless screw being made to work into these teeth, a power is gained for lowering and hoisting the sections. Another method is, to place Iron Rollers on the drawing frames, in proper places, ^{and} simply winding a portion of each chain round the roller wheels and endless, screws may be attached to the rollers, thereby they may be wound, or unwound conveniently. Another great use of these separate powers on the sections are to adapt the ^{shape of the} gradual head of the ship. this is one of the greatest advantages the vertical life boats, have in common over all species of internal planes, it is intended as all the machinery attached to the chains, whether screws or rollers are fixed in exactly the same position between the drawing frames, we propose that to save expence instead of having sufficient gearing attached to each chain to work it, that we just have each chain with a roller or screw, whichever is used, furnished so far as the first motion. then if we have a frame with wheels attached to it, these wheels to have flanges and stand on the top of the drawing frames similar to a Rail Road carriage. this frame containing the requisite powers for working, which may be run along from one chain to the other, and will answer for the whole. That we claim as new and our invention, to avoid confusion we will state under distinct heads,

First. We claim the invention or application of placing the hydrostatic cylinders in a horizontal position whereby we are enabled to make all cylinders move, and likewise have the advantages of applying the moving power at one point. Second. We claim the invention of the self-regulating apparatus as described above taken in connection with the hydrostatics for the purpose of lowering the ship. Third. We claim the drawing frames with these appendages viz. the chains and track wheels as we have applied them to

May 13, 1831

a vertical lift dock for raising ships and other vessels. A pulley has been placed in a horizontal position before for a variety of purposes, such as whaling and chain for hauling up ships on inclined planes, & so in cases of sunken vessels, chains have been used to lift them vertically. This being the case we thought best to premise that we claim the above machinery only as we have combined them together in a fixed stationary machine called a vertical lift dock, and it is the relative position and combined operation of the parts that forms the novelty of our claims.
